UNITED STATES PATENT OFFICE.

VICTOR M. SUMMA, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

STEEL BOX-CAR.

1,021,170.

Specification of Letters Patent. Patented Mar. 26, 1912.

Application filed October 18, 1911. Serial No. 655,312.

To all whom it may concern:

Be it known that I, VICTOR M. SUMMA, residing at St. Louis, Missouri, and being a citizen of the United States, have invented 5 certain new and useful Improvements in Steel Box-Cars, of which the following is a full, clear, and exact description, such as will enable others skilled in the art to which it appertains to make and to use the 10 same, reference being had to the accompanying drawings, which illustrate the preferred form of the invention, though it is to be understood that the invention is not limited to the exact details of construction shown 15 and described, as it is obvious that various modifications thereof will occur to persons skilled in the art.

In said drawings: Figure 1 is a side elevational view of approximately one half of a 20 box car constructed in accordance with this invention. Fig. 2 is a vertical longitudinal sectional view showing the inner face of the side wall illustrated in Fig. 1. Fig. 3 is a transverse vertical sectional view, the 25 left hand side of said figure showing a section taken at the side door and the right hand side of said figure showing a section taken at a point intermediate the side door and end of the car. Fig. 4 is an enlarged 30 fragmentary elevational view illustrating the details of construction at the lower corner of one of the side doors. Fig. 5 is a horizontal sectional view taken on the plane of line 5—5 of Fig. 4. Fig. 6 is a detail 35 vertical sectional view taken on the plane of line 6—6 of Fig. 4, being also an enlargement of the section shown at the lower left hand corner of Fig. 3, for better illustrating the construction at the side door. Fig. 7 40 is a detail sectional view similar to that shown in Fig. 6, but being substantially an enlargement of the section shown at the lower right hand corner of Fig. 3, for better illustrating the construction between the 45 side doors and the car ends.

The object of this invention is to provide a light, but substantial, all-metal, car wall and to so design the same that it may be manufactured at a less cost than walls of 50 the same capacity heretofore built.

To this end the invention comprises a reinforcing member for the wall, said reinforcing member extending continuously beneath the side door opening, having its op-

posite end portions fixed to the side plate 55 and to the sheathing plates and posts in such manner as to permit of the omission of some of the sheathing plates and posts, for forming the door opening without materially affecting the weight sustaining capacity of the wall, said sheathing plates serving as splice plates for connecting said reinforcing member to said side plate and to said posts.

It further provides that the floor sheets 65 be connected with the side connecting member and with adjacent portions of the sheathing plates in such manner as to augment the weight sustaining capacity of said wall members.

It further provides that the floor plates, at the door openings, be so formed and connected to the side connecting member and to the intermediate portion of the continuous reinforcing member, above referred to, as 75 to reinforce said members, and at the same time provide an appropriate door sill covering said members.

Referring to the drawings in which is illustrated the preferred embodiment of the 80 invention, the numeral 1 indicates the center sills, 2 the cross bearers and 2^a the bolsters of the underframe structure.

The opposite side walls of the car being identical one only will be described in 85 detail and the description thereof will obviously apply to both.

The side connecting member comprises a vertically disposed plate 3, extending lengthwise of the car having its upper edge 90 substantially in the plane of the under-surface of the floor plates 4, and a reinforcing angle 5 disposed with one of its flanges up-standing and fixed to the inner surface of the plate 3, and with its other flange projecting inwardly at the lower edge of said first mentioned flange and in the plane of the lower edge of the plate 3. The compound side connecting member thus formed is of L-shape in cross section having its 100 shorter leg projecting inwardly and its longer leg upstanding.

The floor plates 4 extend from side to side of the car resting upon the upper-surfaces of the center sills 1 and transverse members 105 2 and 2^a, and has its opposite longitudinal edges flanged downwardly, as at 6, and fixed to the inner surface of the plate 3 of the

side connecting member along the upper edge thereof, throughout the length of the car, except as follows: Adjacent each of the side posts 7, the flange 6, and a part of the 5 horizontal portion of the floor plate, is cut forming a recess 8, adapted to receive the posts; at the side door the floor plate is extended across the upper edge of the plate 3, of the side connecting member as at 9, and 10 is flanged downwardly across the outer-surface of said plate, as at 10, said down-turned flange having its lower edge in the same plane with the lower edge of the plate 3. The flange 10 extends longitudinally of 15 the car from one of the door posts to the other. The flange 6 is cut away adjacent the door posts, as at 6^a for the passage of a tension member as 16 hereinafter described.

The posts 7 may be of any desired cross 20 section, but are illustrated as comprising rolled angles having one of their flanges as 7^a fixed, by its flat outer surface, to the inner face of the plate 3 and having its other flange 7^b extending inwardly. The 25 lower ends of each of the posts are offset as at 11 for accommodating the upstanding flange of the reinforcing angle 5 of the side connecting member, and said offset portions are fixed to said angle by through rivets, as 30 at 12.

The transverse members 2 of the under-frame are preferably secured to the posts 7, as at 13, said posts serving as angle brackets for connecting said transverse members to 35 the side connecting member.

The sheathing plate or plates as 14 are securely riveted directly to the outer faces of the flanges 7^a of the posts 7, having their lower longitudinal edges offset at the upper 40 edge of the plate 3 and lapping the outer face of said plate and being riveted thereto by through rivets some of which extend through the upstanding flange of the angle 5, others through said flange and through 45 the posts 7, and others through the flange 6 of the floor plate. The upper longitudinal edge of the sheathing plate 14 is fixed to the inner vertical surface of the side plate 15.

A continuous tension bar as 16 extends 50 from the side plate, at one of the transom posts 7^c, above the car bolster, at one end of the car, to the side plate at a corresponding location near the opposite end of the car, having its intermediate portion depressed 55 and extending beneath the floor plate at the door opening. The tension bar 16 is preferably of uniform cross section having one of its flat faces resting against the inner-surface of the sheathing plates and being fixed 60 thereto throughout its length, except at the door where said sheathing plates are omitted. At this point the tension bar engages the inner alined surface of the plate 3 of the side connecting member 2 and is fixed 65 thereto.

At opposite sides of the door openings the end portions of the tension bar extend diagonally upward to the side plate, said diagonally disposed portions intersecting the 70 posts 7 and said posts being formed with suitable recesses 16^a Fig. 3 adapted to accommodate said tension bar so as to provide an even surface for the attachment of the sheathing plates 14.

The sheathing plates 14 being fixed to 75 the posts 7 and to the tension bar, form connecting plates rigidly connecting said tension bar to said posts. Likewise at the ends of the tension bar the plates 14 being fixed to the posts 7^c and to the side plate, 80 and to the tension bar, form gusset plates rigidly connecting the ends of the tension bar to the side plate and to said posts 7^c. Supplemental gusset plates 17 are fixed to the ends of the tension bar, and to the adjacent posts, and to the side plate. The sheathing plates serve also as means for connecting the posts 7, 7^c, the side plate and the side connecting member.

Supporting braces or tension members as 90 18 extend from adjacent the upper ends of the tension bar 16 downwardly to the ends of the car for supporting the end sills, said braces being fixed to the sheathing plates, and to the side plate, and to the supplemental gusset plates, similarly as are the 95 ends of the bar 16, said gusset forming a bond between the adjacent ends of said bar 16 and braces 18 for equalizing their respective stresses upon the upper ends of the 100 posts 7^c. The side plate 15 extending between and being fixed to the adjacent ends of the bar 16 and braces 18 and to the posts, 105 serve as means for reinforcing the connection between said bar and braces and said posts.

The posts 7 at opposite sides of the door are offset at their lower ends at the floor level to accommodate the bar 16, and to 110 form a shoulder as 19 under which the bar is arranged to engage. Owing to the greater thickness of the tension member 16, a filler block 20 is interposed between the lower end of the post and the upstanding flange of the angle 5.

It will be noted that the down-turned flange of the floor sheet 4, being disposed vertically and being fixed to the vertical face of the side connecting member, adds materially to the weight sustaining capacity 115 of said member.

With this construction a girder is formed, of simple design, having as its compression chord the side plate 15 and as its tension chord the side connecting member reinforced by the tension bar 16 and by the flanges of the floor sheets, and by the lower portions of the sheathing plates. Obviously 125 the roof structure, forming no particular part of this invention, but being fixed to the 130

side plate, adds materially to the strength of said side plate as a compression member.

What I claim is:

1. In a car, a side wall formed with a door opening and comprising a side plate, vertical posts fixed to said side plate, and a continuous tension bar of constant cross section extending between the upper ends of some of said posts having its intermediate portion depressed and extending beneath said door opening.
2. In a car, a side wall formed with a door opening and comprising a side plate, vertical posts fixed to said side plate, and a continuous tension bar extending between the upper ends of some of said posts having its intermediate portion depressed and extending beneath said door opening, and said depressed portion being fixed to others of said posts.
3. In a car, a side wall formed with a door opening and comprising a side plate, vertical posts fixed to said side plate, and a continuous tension bar extending between the upper ends of some of said posts having its intermediate portion depressed and extending beneath said door opening, and some of said posts being formed with recesses and the depressed portion of said tension bar being received in said recesses.
4. In a car, a side wall formed with a door opening and comprising a side plate, vertical posts fixed to said side plate, and a continuous tension bar extending between the upper ends of some of said posts having its intermediate portion depressed and extending beneath said door opening, said posts being recessed and said tension bar being extended through said recesses.
5. In a car, a side wall formed with a door opening and comprising a side plate, vertical posts fixed to said side plate, and a continuous tension bar extending between the upper ends of some of said posts having its intermediate portion depressed and extending beneath said door opening, some of said posts being recessed intermediate their ends and others of said posts being recessed adjacent their ends, and said tension bar being extended through said recesses.
6. In a car, a side wall formed with a door opening and comprising a side plate, a side connecting member and a continuous tension bar having its opposite ends fixed to said side plate and having its intermediate portion depressed and extending beneath said door opening, and said depressed portion being fixed to the inner surface of said side connecting member.
7. In a car, a side wall formed with a door opening and comprising a side plate, a side connecting member, sheathing plates, and a continuous tension bar having its end portions fixed to said side plate and

having its intermediate portion depressed and extending beneath said door opening, said tension bar being fixed to said sheathing plates.

8. In a car, a side wall formed with a door opening and comprising a side plate, a side connecting member, vertical posts, sheathing plates, and a continuous tension bar having its opposite ends fixed to said side plate and having its intermediate portion depressed and extending beneath said door opening, said tension bar being disposed between said posts and sheathing plates.

9. In a car, a side wall formed with a door opening and comprising a side plate, a side connecting member, vertical posts, sheathing plates, and a continuous tension bar having its opposite ends fixed to said side plate and having its intermediate portion depressed and extending beneath said door opening, said posts being formed with recesses and said tension bar being disposed between said posts and said sheathing plates and extending through said recesses.

10. In a car, a side wall formed with a door opening and comprising a side plate, a side connecting member, vertical posts, sheathing plates, and a continuous tension bar having its opposite ends fixed to said side plate and having its intermediate portion depressed and extending beneath said door opening, said sheathing plates being fixed to said posts and said posts having parts spaced from said sheathing plates forming recesses, and said tension bar extending through said recesses.

11. In a car, a wall structure formed with a door opening and forming a girder whose compression member is the side plate supported by posts extending upwardly from points adjacent the car bolsters, and whose tension member is fixed to said side plate adjacent said posts and extends beneath said door opening.

12. In a car, a wall structure formed with a door opening and forming a girder whose compression member is the side plate supported by posts extending upwardly from points adjacent the car bolsters, and whose tension member is fixed to said side plate adjacent said posts and extends beneath said door opening, and stiffening members extending between and connecting said compression and tension members intermediate their length.

13. In a car, a wall structure formed with a door opening and forming a girder whose compression member is the side plate supported by posts extending upwardly from points adjacent the car bolsters, and whose tension member is fixed to said side plate adjacent said posts and extends beneath said door opening, stiffening members extending between and connecting said compression

- and tension members intermediate their length, and sheathing plates serving as means connecting said stress members together.
14. In a car, a wall structure formed with a door opening and forming a girder whose compression member is the side plate supported by posts extending upwardly from points adjacent the car bolsters, and whose tension member is fixed to said side plate adjacent said posts and extending beneath said door opening, stiffening members extending between and connecting said compression and tension members intermediate their length, and sheathing plates serving as means connecting said stiffening members to said stress members.
15. In a car, a wall structure formed with a door opening and comprising a girder whose compression member is the side plate supported by posts extending upwardly from points adjacent the car bolsters, and whose tension member is fixed to said side plate, stiffening members extending between and connecting said compression and tension members intermediate their length, and sheathing plates serving as means connecting said stiffening members to said stress members, and splice plates connecting said stress members together and to said posts.
16. In a car, a side wall formed with a door opening and comprising a side plate, a side connecting member, and a continuous tension bar having its opposite ends fixed to said side plate and having its intermediate portion depressed and extending beneath said door opening, and sheathing plates serving as means connecting said tension bar to said side connecting member.
17. In a car, a side wall formed with a door opening and comprising a side plate, a side connecting member, and a continuous tension bar having its opposite end portion connected with said side plate and having its intermediate portion depressed and extending beneath said opening, and stiffening members connecting said tension member to said side connecting member.
18. A car wall comprising vertical posts extending upwardly from points adjacent the car bolsters, a tension member for said wall disposed between said posts and having diagonal portions engaging the upper ends of said posts, oppositely disposed diagonal braces beyond said posts converging with the diagonal portions of said tension member at said posts, and sheathing plates serving as means connecting said tension member to said braces and connecting said tension member and braces to said posts.
19. A car wall comprising vertical posts extending upwardly from points adjacent the car bolster, a tension member for said wall connecting said posts and having diagonal portions engaging the upper ends of said posts, oppositely disposed diagonal
- braces beyond said posts converging with the diagonal portions of said tension member at said posts, and sheathing plates serving as means connecting said tension member to said braces and connecting said tension member and braces to said posts.
20. A car wall comprising vertical posts extending upwardly from a point adjacent the car bolsters, a tension member for said wall disposed between said posts and having diagonal portions engaging the upper ends of said posts, oppositely disposed diagonal braces beyond said posts, converging with the diagonal portions of said tension member at said posts, and a side plate connecting said posts and serving as means connecting said tension member to said braces and connecting said tension member and braces to said posts.
21. In a car, the combination with a side connecting member comprising a vertically disposed plate, of a floor plate formed with a pendant flange fixed to said side connecting member adapted to reinforce said side connecting member and a continuous tension member extending below the side floor plate and being connected with said flange and extending thence upwardly toward opposite ends of the car body.
22. In a car, the combination with an underframe comprising transverse members, of a side connecting member for said transverse members, posts fixed to said side connecting member and forming angle brackets connecting said transverse members to said side connecting member, and a floor plate fixed to said side connecting member and being formed with recesses adapted to receive said posts.
23. In a car, the combination with a side connecting member, of a floor plate fixed to said side connecting member for stiffening said member and sheathing plates fixed to said side connecting member and to said floor plate for stiffening said side connecting member.
24. In a car, a side wall formed with a door opening and comprising a side plate, vertical posts fixed to said side plate, a continuous tension bar extending between the upper ends of some of said posts having its intermediate portion depressed and extending beneath said door opening, and a floor plate extending across said tension bar.
25. In a car, a side wall formed with a door opening and comprising a side plate, a continuous tension bar having its opposite ends fixed to said side plate and having its intermediate portion depressed and extending beneath said door opening, and a floor plate extending above and being fixed to said tension bar.
26. In a car, a side wall formed with a door opening and comprising a side plate, a side connecting member, a continuous ten-

- sion bar having its opposite ends fixed to said side plate and having its intermediate portion depressed and extending beneath said door opening, and a floor plate extending across said tension bar and being fixed to said side connecting member. 5
27. In a car, the combination with a wall formed with a door opening and comprising a side connecting member, of a floor plate fixed to one face of said side connecting member at opposite sides of said door opening and to the opposite face of said side connecting member at the door opening. 10
- 15 28. In a car, the combination with a wall formed with a door opening and comprising a side connecting member, of a floor plate fixed to the inner face of said side connecting member at opposite sides of said door opening and to the outer face of said side connecting member at the door opening. 20
- 25 29. In a car, a side wall formed with a door opening and comprising a side plate, a side connecting member, a continuous tension bar having its opposite ends fixed to said side plate and having its intermediate portion depressed and extending beneath said door opening, door posts formed with recesses for receiving said tension bar, and 30 a floor plate formed with recesses for receiving said posts and being fixed to the inner surface of said side connecting member at opposite sides of said door opening, and extending across said tension member 35 and being fixed to the outer surface of said side connecting member at the door opening. 30
- 40 30. In a box car, an underframe, uprights or posts rising therefrom, a floor above said underframe and a tension member extending from one of said posts to another of said posts and under a portion of said floor. 90
- 45 31. In a car, a combination comprising underframe members, upright members rising thereabove, a tension member connected with said upright members, above said underframe, near its ends and a floor overlapping said tension member intermediate the ends of said tension member. 95
- 50 32. In a car, a combination comprising upright members, a continuous tension member connected with said members near their upper part, said tension member being bent downwardly intermediate its ends and a floor plate connected to said tension member. 55
33. In a car, a combination comprising upright members, a continuous tension member connected with said members near their upper part, said tension member being bent downwardly intermediate its ends and a floor plate connected to and overlapping said tension member. 60
34. In a box car, an underframe, posts, sheathing, a continuous tension member connected directly to said underframe, said posts and to said sheathing, and a floor sheet secured by direct connection to an intermediate part of said tension member. 65
35. In a car having a door opening, the combination comprising transom posts, a tension member connected with said transom posts near their upper ends, an underframe stiffened below said door opening by direct connection with an intermediate part of said tension member and sheathing secured directly to said tension member. 70
36. A car construction comprising an underframe, posts and diagonals, a continuous tension member connected with upper parts of said posts and with said underframe intermediate its ends, and sheathing plates secured directly to said underframe, posts, diagonals and said tension member. 80
37. In a car side wall, vertical posts, diagonals, a plate extending substantially the length of said wall at the lower part thereof, a tension member connected with said plate intermediate its ends and with some of said posts near its ends and a sheathing secured directly to all of said members. 85
38. In a car construction, the combination comprising a tension member, floor sheets secured to opposite sides of said tension member and a side sheathing secured to said tension member. 90
39. In a car construction, the combination comprising a longitudinally disposed member, floor sheets overlapping and secured to opposite sides of said member. 95

In witness whereof I have hereunto set my hand in the presence of two witnesses.

VICTOR M. SUMMA.
